UNITED STATES PATENT OFFICE.

CLARENCE C. SHIPP, OF INDIANAPOLIS, INDIANA.

AUTOMATIC VENTILATOR.

1,388,611.

Specification of Letters Patent. Patented Aug. 23, 1921.

Application filed January 19, 1920. Serial No. 352,357.

To all whom it may concern:

Be it known that I, CLARENCE C. SHIPP, a citizen of the United States, residing at Indianapolis, in the county of Marion and State of Indiana, have invented new and useful Improvements in Automatic Ventilators, of which the following is a specification.

Fresh air intakes for crowded rooms such as school-rooms, legislative and convention halls, offices, factories, and the like, are essential to the vigor, efficiency, and health of the occupants. Damper-regulated conduits receiving air from the outside, and discharging it into such occupied rooms initially warmed by passing between coils have been provided, but so far as I know the dampers have been manually opened and closed, which introduces the human element of wrong judgment, and of neglect.

The object of this invention is so to connect the damper with a thermostat that the outside air supply will be automatically regulated, causing the damper to close at about 68 degrees, and to remain closed at that and lower temperatures and to gradually open above 68 degrees to a full open position at about 72 degrees, at and above which temperature it remains open.

I have found this particularly beneficial in the ventilation of school-rooms. At night when the fires are banked and the temperature falls below 68 degrees, all of the dampers close automatically. When the janitor fires up in the morning, and the school-room temperature reaches and exceeds 68 degrees the dampers correspondingly open, reaching full open position at 72 degrees, and remaining open at 72 degrees and above. Should a cold wind be blowing when the fires are renewed in the morning, the damper on the windward side of the house will remain closed if the temperature of the school-room is so affected that 68 degrees is not reached; or should a shifting of the wind occur later causing an inrush of cold air, and a lowering of temperature formerly at or above 72 degrees, the dampers in the supply there will correspondingly close until at 68 degrees and under, the closure will be complete.

In practice I have attained the best results by inclosing part of the radiator sections within a vertical sheet-metal box which is open at its top, and communicates at its lower end with a horizontal box leading through the adjacent wall of the building to

the outside air; and an object of my invention is to introduce the thermostat in a side of the radiator-box between the radiator and near wall of the room and insulate it from direct radiation from the heater, while subjecting it to the temperature of the room atmosphere.

I accomplish the above, and other objects which will hereinafter appear, by the mechanism illustrated in the accompanying drawings, in which—

Figure 1, is a vertical section showing a radiator, housed within a radiator box into which a wall box discharges, the latter having a damper, and means for automatically opening and closing the damper by a thermostat located in a wall of the radiator-box.

Fig. 2, is a section on the line 2—2 of Fig. 1 showing thermostat levers and their connections; and Fig. 3 is a fragment, from the line 3—3 of Fig. 1, showing a part of the inner wall of the radiator-box with particular reference to the thermostat insulation, and the fresh air damper indicator.

Like characters of reference indicate like parts in the three views.

The floor joist 4, supports a floor 5, and itself is supported by a wall 6, having an opening slightly above the floor in which a metal wall box 7, is built. This box 7 communicates with the outside air at one end, and at its other end discharges into a vertical sheet-metal radiator-box 8, which surrounds some of the sections of a radiator 9, of usual construction. The top of the radiator-box is open, whereby fresh air from the outside of the building is discharged into the room after being warmed by passing through the radiator 9.

The outer end of wall box 7, is provided with storm louvers 10, and an insect-screen 11, and, in further, with a damper 12, hinged at its upper edge so as to be more or less opened by swinging it on its hinges. To this end it has ears to which one end of a link 13 is pivoted. The other end of link 13, is pivoted to a lever 14, which has its lower end pivoted to the floor of the wall-box. A push-bar 15, is pivoted at one end, to the upper end of lever 14; and, in my early installations, the other end of bar 15 was extended through a suitable opening in the base of the radiator-box into convenient access for manual adjustment of the damper by a person in the room.

The mechanism thus far described is

shown in previous patents issued to me, and is objectionable because not automatic in its operation, but is dependent upon human attention, and subject to human neglect.

5 In my present invention, instead of extending the push-bar through the front of the radiator-box, I bend the end up as shown, and attach a chain 16, which is carried back and under a sheave 17, and 10 thence up outside of the radiator box, to a vertically reciprocating bar 18, which is connected by a pair of rods 19, 19, with the lower arms of the respective levers 20, and 21, of a thermostat. The latter is actuated by the influence of the temperatures of the air in the room on sensitive substances, as mercury, ether, or the like, confined between a pair of sheet-metal disks which vary in their distances apart with the 20 expansion, and contraction, of the heat-sensitive substance confined between them.

One of the said metal disks, and preferably the outer one 22, I prefer to form integrally from the material of the radiator-box 8, by a suitable stamping operation. The necessary depth of the recess will not be anywhere as great in proportion as shown in Fig. 1, because all of the proportions are here purposely exaggerated for 30 greater clearness in illustration. The inner disk 23, is soldered, or otherwise tightly and securely united at its edges, to the disk 22, after the mercury, or ether is added. The integral annular member 24, uniting disk 35 22, with the back of box 8, has perforations 25, for the free circulation therethrough of the surrounding air of the room; and, to protect the sensitive contents between the disks from the direct heat from 40 the radiator, I cover the mouth of the recess with asbestos 26, which is retained by a metal plate 27.

Mounted between the disk 23, and asbestos 26, and supported from the member 24, is a 45 tripod 28, which supports a bar 29, to which the levers 20, and 21, are pivoted, (see Fig. 2). The inner short arms of the levers are connected by rods 30, 30, with the two ends of a pin 31 mounted in a lever 32, which is 50 pivoted to the tripod 28. The opposite end of lever 32 is bifurcated, and, between the resulting arms, a friction-wheel 33, is mounted. The latter makes rolling contact against the disk 23, (see Fig. 1) whereby the lever 55 32 is moved in a direction to raise levers 20, and 21, when the disk 23 is forced toward it by the expansion of the material between the two disks. This raises bar 18, and pulls on chain 16, thereby moving the bar 15, longitudinally, and operating lever 14, and link 60 13, to open the damper 12. The bar 15, is guided and partially supported by a channelled friction-wheel 34.

Supported by the back member of the 65 radiator-box is a vertical plate 35, bearing

the legend "Shut" on that face which is toward the room, and below the legend is a fixed vertical plate 36 between which, and plate 35, is a space in which the movable plate 37 is slidingly mounted. On the latter 70 is a legend "Open" which is covered and hid by the plate 36, while plate 35 is behind it, but when raised above 36, the plate 35 covers and hides the legend "Shut" and exposes the legend "Open." 75

The required movement is accomplished by a vertical rod 38, on the upper end of which the plate 37 is mounted.

The rod 38 terminates at its lower end in a lateral member 39, which passes through a 80 suitable vertical slot in box 8, and through a vertical slot in bar 18. A slot is required in bar 18, because the travel of the latter is greater than the desired movement of plate 37, and the slot affords the necessary lost 85 motion. A slot in box 8, is required to allow the bent end of the rod 38, to reach bar 18, and the bottom of the slot in the box 8, limits the downward movement of the rod.

In summer when the temperature is high 90 enough to so act on the thermostat as to keep the damper constantly open, it is also desirable to keep the damper closed in order to exclude dust, and on such occasions the chain 17, is unhooked from the bar 18. A 95 ring R on the end of chain 17, is too large to pass through the hole in box 7, and remains in reach, ready to be hooked to the bar 18, to restore the operativeness of the device. A water pan 40 in box 8 in front 100 of the radiator is kept from freezing, as a result of carelessness in not closing the damper, by the automatic closing of same as here provided.

Starting with the device closed as shown 105 in Fig. 1, an expansion of the mercury between the sheet metal disks 22 and 23 expands with an increase of temperature in the room and moves the lever 32 in a direction to lower the short arms of the levers 20 110 and 21 to which it is attached by links 30, thereby raising bar 18 to which the long arms of levers 20 and 21 are connected by links 19. The upward movement of bar 18 so pulls on the chain 16 as to slide the bar 115 16 toward the lever 14 and swings the lever 14 toward the damper 12 with which it is connected by bar 13, and opens the damper thereby admitting outside air into the room. The lowering of the bar 18 lowers the rod 120 38 and its plate so the legends will be changed.

While I have here described the best form of my invention now known to me, various substitutes are possible in the sensitive-to-heat element, and the mechanism for opening and closing the damper by the expansion and contraction of said element is subject to modification without departing from the spirit of my invention. I therefore, do not 125 130

desire to be limited any more than is required by the appended claims.

I claim—

1. The combination, with a heat-radiator, of a radiator-box surrounding the radiator having an outward recess formed in its wall, a disk-closure forming a sealed chamber in said recess, the outer wall of the recess forming one of the walls of the sealed chamber, a 5 heat-sensitive substance in said chamber moving said disk closure by its expansion, mechanism assembled in said recess for multiplying the movement of the disk closure, a cold-air box discharging into the radiator- 10 box, a damper in the cold-air box, and means for operatively connecting the damper with said multiplying mechanism.
2. The combination, with a heat-radiator, of a radiator-box surrounding the radiator having an outward recess formed in its wall, a disk-closure forming a sealed chamber in 15 said recess, the outer wall of the recess forming one of the walls of the sealed chamber, a heat-sensitive fluid in said chamber moving said disk-closure by expansion and contraction, mechanism assembled within 20 said recess for multiplying the movement of the disk-closure, an insulating material between said multiplying mechanism and 25 radiator, a cold-air box discharging into the radiator-box, a damper in the cold-air box 30

and means for operatively connecting the damper with said multiplying mechanism.

3. The combination with a heat radiator, of a sheet metal radiator-box having a recess 35 pressed in its wall, and a disk closure forming a sealed chamber in said recess the outer wall of the recess forming one of the walls of the sealed chamber.

4. The combination with a heat radiator, 40 of a sheet metal radiator-box having a recess pressed in its wall, a thermostat chamber formed by closing off a portion of the recess, the outer wall of the recess forming one of the walls of the sealed chamber, and 45 an insulation protecting the thermostat chamber from the direct heat of the radiator.

5. The combination with a heat radiator, of a sheet metal radiator box having a recess 50 pressed in its wall, a disk closure forming a sealed thermostat chamber in said recess, the outer wall of the recess forming one of the walls of a sealed chamber, and a heat insulation closing the recess from the interior of the box, the walls of said recess 55 between the insulation and closure having openings for the free circulation of air therethrough.

Signed at Indianapolis, Indiana, this the 60
13th day of January, 1920.

CLARENCE C. SHIPP.
